[57] CLAIM

The ornamental design for a control unit for a vehicular two-way radio or similar article, as shown and described.

DESCRIPTION

FIG. 1 is a top plan view of a control unit for a vehicular two-way radio or similar article showing my new design;

FIG. 2 is a front elevational view thereof;

FIG. 3 is a bottom plan view thereof;

FIG. 4 is a rear elevational view thereof;

FIG. 5 is a left side elevational view thereof;

FIG. 6 is a right side elevational view thereof; and,

FIG. 7 is a top, front and left side perspective view thereof.

The broken line showing of the buttons in FIGS. 2 and 7 is for illustrative purposes only and forms no part of the claimed design.

FIG. 1

FIG. 2

FIG.5
